UNITED STATES PATENT OFFICE.

ROCK TRISTANO, OF CHICAGO, ILLINOIS.

BRACING MEMBER FOR LININGLESS COAT SLEEVES.

Application filed December 8, 1920. Serial No. 429,244.

To all whom it may concern:

Be it known that I, ROCK TRISTANO, a citizen of the United States, and a resident of the city of Chicago, county of Cook, and State of Illinois, have invented certain new and useful Improvements in Bracing Members for Liningless Coat Sleeves, of which the following is a specification.

My invention relates to a reinforcing member, which I call a sleeve-head, for a liningless coat-sleeve, and has for its object the provision of means insertable in the sleeve for reinforcing the upper part of said sleeve.

In coats manufactured for wear in tropical climates the sleeves are made without lining, and such sleeves are subject to wrinkling at their junction with the shoulder of the coat. It is my object to overcome such wrinkling, for which purpose I attach a reinforcing member or sleeve-head to the coat at the place where the sleeve and coat are attached together, and allow this reinforcing member to protrude into the upper portion of the sleeve as above set forth, the abrupt change from the skeleton lined shoulder to the liningless sleeve is overcome, and the wrinkles ordinarily formed at the upper portion of the sleeve are substantially diminished.

Other objects will appear hereinafter.

The invention consists in the combinations and arrangements of parts hereinafter described and claimed.

The invention will be best understood by reference to the accompanying drawings forming a part of this specification, and in which,

Fig. 1, is a fragmentary front elevation of a coat with my re-inforcing member attached thereto and shown in section;

Fig. 2, is a perspective view of the re-inforcing member;

Fig. 3, is a pattern from which the re-inforcing member is formed by folding it along the dotted lines;

Fig. 4, is a modified form of re-inforcing member which is continuous around the sleeve; and

Fig. 5, is an enlarged detail view partly in section, showing the connection of the re-inforcing member with the shoulder of the coat.

The form of my invention illustrated in the drawing comprises a coat 6 and a sleeve 7 attached thereto. At the junction 8 of the coat and sleeve the reinforcing member or sleeve-head 9 is attached, as by sewing it to the connection of the coat and sleeve, that is, to the parts of cloth of the sleeve and of the shoulder of the coat which parts are stitched together and connected to the lining, as shown in Figs. 1 and 5, or to the skeleton lining 10, adjacent the junction of the sleeve with the coat, the member 9 thus extending into the interior of the sleeve and bearing beneath the upper portion thereof, thereby reinforcing the sleeve adjacent the shoulder seam. This member 9 may be formed from an oblong or substantially oval-shaped pattern, as shown in Fig. 3, which is folded along the longitudinal middle line, the edge 11 being fastened to the junction of the sleeve and shoulder or body portion of the coat and the doubled or folded over part 12 being permitted to protrude into the sleeve.

In Fig. 4 a re-inforcing member or sleeve-head 9' is shown which is continuous around the arm hole of the coat, the upper half being effective as the main reinforcing portion and the lower half being in addition effective as a sweat band.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent, is:—

1. A reinforcing member for a liningless sleeve of a tropical coat, formed of an oblong piece of material folded and fastened to the coat at the connected upper part of the sleeve and the shoulder of the coat, and protruding into the sleeve to engage beneath the upper part thereof for the purpose of avoiding an abrupt drop of said sleeve at said connection.

2. A reinforcing member for the sleeve of a tropical coat, consisting of an oval shaped

piece of cloth, folded over and stitched with its joined edges to the connected material of the sleeve and the shoulder of the coat, and having its folded part protruding into the sleeve engaging and movably bearing beneath the upper part thereof.

In testimony whereof I have signed my

name to this specification in the presence of two subscribing witnesses.

ROCK TRISTANO.
